UNITED STATES PATENT OFFICE.

FRANK A. COMSTOCK, OF COLUMBUS, OHIO.

VEHICLE-SEAT.

SPECIFICATION forming part of Letters Patent No. 254,115, dated February 28, 1882.

Application filed September 30, 1881. (No model.)

To all whom it may concern:

Be it known that I, FRANK A. COMSTOCK, a citizen of the United States, residing at Columbus, in the county of Franklin and State 5 of Ohio, have invented a new and useful Improvement in Vehicle-Seat-Backs, of which the following is a specification.

My invention relates more particularly to seat-backs made of metal; and the novelty 10 consists in making them in sheet-metal sections having their proximate edges turned back toward the body of the sections, and in uniting the sections thus formed by means of strong strengthening corner-pieces adapted to receive 15 the turned-back edges of the sections, whereby a stronger seat-back is obtained, which is cheaper, on account of the less waste of material in making it, over those which are made of a single piece bent into shape.

20 In the accompanying drawings, Figure 1 is a perspective view of a vehicle-seat back made in three pieces or sections, the sides being attached to the back and firmly held by my locking device, which in this instance is applied 25 on the inside of the back's sections at their points of connection or angles. Fig. 2 is a rear view of a back, showing the locking device applied on the outside at point of connection. Fig 3 is an enlarged detail view, showing part 30 of the seat-back and side with their vertical edges turned back, over which a piece of metal made to embrace the turned edges is placed and fastened in any suitable manner, thus forming a dovetailing slide, and locking or firmly holding the parts together. Fig. 4 is an enlarged 35 detail view, showing the fastening applied to the inside of the back. Fig. 5 is a similar view with the fastening on the outside.

A is the rear of the seat-back, and B and C 40 are the sides.
a, b, and c are the ordinary flanges to which the seat-bottom is attached.

a', b', and c' are the ordinary top flanges to the back and sides of vehicle-seats, for strengthening and finishing purposes.

A' and B' are the turned edges or flanges of the seat-back and sides. These flanges are turned back in opposite directions to each other, and are embraced by the metal dovetailing piece D' or E. This piece D' or E is made 45 with its vertical edges turned inwardly in opposite directions, and it is preferably angular in cross-section, so that its interior will correspond with flanges A' and B, and by sliding it over these flanges a snug fit will be secured 50 and the parts held firmly together.

55 It will be observed that it is immaterial whether the attachment be made on the inside or outside of the back. The same firmness is secured in both cases, and it is only a matter of 60 individual preference which mode is adopted.

The corners of the seat-back and dovetailed slide may be subjected to a die, by which the flanges are pressed flat and close, forming a 65 smooth clean corner, the metal used being much thinner than indicated by the drawings.

By my invention I am enabled to manufacture seat-backs with much less waste of material than by the methods heretofore in use, and it is apparent that the facilities for repairs are 70 also rendered greater.

Having thus described my invention, what I claim is—

A vehicle-seat back composed of sheet-metal sections having their proximate edges turned 75 back toward the body of the sections, and strong strengthening-corners having grooves for the reception of the turned-back edges of the sections, and operating to hold the sections firmly together, substantially as described.

FRANK A. COMSTOCK.
